WIRE STRETCHING AND LOOP FORMING DEVICE

Theodore S. Wright, Sumter, S. C., assignor of
one-third to Randolph L. Wright, Sumter,
S. C.

Application October 9, 1939, Serial No. 298,684

5 Claims. (Cl. 140—118)

My invention relates to a wire loop forming and wire stretching device for securing a length of wire about an object and has as one of the principal objects thereof the provision of a device 5 of the above described character so constructed and arranged wherein a loop is formed on the end of a length of wire and for stretching a section of said wire through said loop whereby said length of wire may be maintained in fixed relation about the object.

Another object of my invention is to provide a device of the above described character which is simple in construction, durable in use, efficient in operation and economical in manufacture.

15 Other objects and advantages will be apparent from the following description, appended claims and annexed drawing.

Referring to the drawing wherein like reference characters designate like parts throughout 20 the several views:

Figure 1 is a top plan view, partly in section, of a lubricant shroud arranged about the drive shaft of a motor vehicle between the end of the transmission casing and the opposite end of the 25 universal joint, said shroud being secured in said position by means of lengths of wire formed with a loop and stretched by my novel form of device.

Figure 2 is a vertical longitudinal section of my 30 invention.

Figure 3 is an end elevation of my invention.

Figure 4 is a fragmentary end elevation of my 35 invention and illustrating a finished loop on the end of a wire associated therewith.

Figure 5 is a side elevation of Figure 4.

Figure 6 is a transverse sectional view of my 40 invention illustrating the same as applied in wire stretching position with respect to the shroud depicted in Figure 1.

Figure 7 is a fragmentary end elevation, partly 45 in section, of my invention illustrating the same in another position with respect to the shroud.

Figure 8 is a fragmentary transverse sectional view of the shroud and illustrating a length of wire in completed formation extending there- 50 around.

In order to teach my invention and its use, as illustrated in the drawing, I utilize by way of example only, a lubricant shroud 5 arranged about a shaft between the opposed ends of a transmission casing 6 and a universal joint 7 and which shroud is secured about said shaft by means of a pair of lengths of wire 8 extending through and about said shroud, the lengths of wire 8 having been formed with loops 9 and over- 55 lapped ends 10 by the use of my invention, it

being distinctly understood that the shroud per se forms no part of the present invention as the latter may be employed for securing lengths of wire about various other objects as desired.

As illustrated in the drawing, my invention 5 comprises a barrel 11 formed with a longitudinally extending bore 12 which receives therethrough an end section 13 of a length of wire 8. The barrel is rotatably mounted in the bifurcated or forked ends of an arm A hereinafter more fully 10 described. One end of the barrel 11 is provided with a hook-like member 14 extending therefrom and defining a seat which receives thereon a transversely disposed end 15 of a loop 16 which has previously been formed on the end section 13 15 of the wire. Said member serves to maintain the end 15 in fixed relation with the barrel upon rotation of the loop with respect to the barrel. The loop may be rotated by means of grasping the same with a pair of pliers or the like or rotating 20 the end section of the wire 13. When the loop is thus rotated with respect to the barrel, the member 14 functions to twist or enwrap the end 15 about the end section 13 adjacent the loop 16 25 whereby to completely form and maintain the loop in fixed relation with respect to the end section 13.

As heretofore stated, the barrel is rotatably mounted within the forked ends 18 of the arm A, the latter having connected sections 19. The 30 barrel, adjacent the outer sides of the ends 18, is formed with circumferentially extending grooves 20 in which are mounted split rings 21 to maintain said barrel within the arm A as clearly 35 illustrated in the drawing.

The opposite end of the barrel 11 is fashioned with a transversely extending passage 22 for receiving the end of a handle 23 whereby said barrel may be rotated with respect to the arm A and for a purpose hereinafter more fully described. 40 The barrel is also fashioned, between its ends, with a transversely extending bore 24 for receiving the opposite end of the wire 8.

Upon formation of the loop on the end section 13, as heretofore described, the length of wire is 45 removed from the barrel and the opposite end section inserted through and about the shroud 5, with said opposite end section disposed through the loop 16. When the length of wire is thus arranged, said opposite end section is inserted 50 through an opening 25 formed in the opposite end of the arm A, and upwardly into the bore 24 of the barrel with said opposite end of the arm engaging the loop 16 as clearly illustrated in Figure 6. When the parts are thus arranged, the barrel 55

is rotated with respect to the arm A thereby winding said opposite end of the length of wire about the barrel and effecting tightening of the wire about the shroud. When the wire 5 has become sufficiently tight about the shroud, the arm A is moved in a direction away from the loop and toward the shroud to form a hooked portion 26 extending through said loop 16 whereupon the wire is cut and the free end pressed inwardly to secure the same fixed to the loop.

From the foregoing, it will be apparent that I have provided a simple and efficient device for forming loops on the end of a length of wire and stretching said wire through said loops.

15 It is also obvious that the invention is not confined to the herein described use therefor as it may be utilized for any purpose to which it is adaptable. It is therefore to be distinctly understood that the invention is not limited to the specific construction as illustrated and described, as the same is only illustrative of the principles of operation, which are capable of extended application in advance forms, and that the invention comprehends all construction within the scope of 20 the appended claims.

25 What is claimed is:

1. A device of the character described, comprising, a barrel having a longitudinal bore adapted to receive therethrough an end section 30 of a length of wire for encircling arrangement about an article, one end of said barrel provided with a member extending therefrom and defining a seat for receiving a transversely disposed end of a loop formed on the end of said end section 35 for maintaining the same in fixed relation with respect to the barrel upon relative rotation of the loop and barrel to enwrap said transversely disposed end about said end section adjacent said loop, an arm having one end connected to said 40 barrel for relative rotation and formed with a wire receiving passage extending therethrough, said barrel formed with a transverse bore between its ends and registering with said passage for receiving the end of the opposite 45 end section of said length of wire when said opposite end section is disposed through said loop and said passage for tightening said length of wire about said article upon rotation of said barrel with respect to said arm and movement of 50 said arm with respect to said loop and in a direction away from the latter.

2. A device of the character described, comprising, a barrel having a longitudinal bore adapted to receive therethrough an end section 55 of a length of wire for encircling arrangement about an article, one end of said barrel provided with a member extending therefrom and defining a seat for receiving a transversely disposed end of a loop formed on the end of said end section 60 for maintaining the same in fixed relation with respect to the barrel upon relative rotation of the loop and barrel to enwrap said transversely disposed end about said end section adjacent said loop, an arm having one end connected to said 65 barrel for relative rotation and formed with a

wire receiving passage extending therethrough, said barrel formed with a transverse bore between its ends and registering with said passage for receiving the end of the opposite end section of said length of wire when said opposite end section is disposed through said loop and said passage for tightening said length of wire about said article upon rotation of said barrel with respect to said arm and movement of said arm with respect to said loop and in a direction away from the latter, and means for rotating said barrel with respect to said arm.

3. A device of the character described, comprising, a barrel having a longitudinal bore adapted to receive therethrough an end section of a 15 length of wire for encircling arrangement about an article, one end of said barrel provided with a member extending therefrom and defining a seat for receiving a transversely disposed end of a loop formed on the end of said end section for 20 maintaining the same in fixed relation with respect to the barrel upon relative rotation of the loop and barrel to enwrap said transversely disposed end about said end section adjacent said loop, an arm having one end connected to said 25 barrel for relative rotation and formed with a wire receiving passage extending therethrough, said barrel formed with a transverse bore between its ends and registering with said passage for receiving the end of the opposite end section of said 30 length of wire when said opposite end section is disposed through said loop and said passage for tightening said length of wire about said article upon rotation of said barrel with respect to said arm and movement of said arm with respect to said 35 loop and in a direction away from the latter, the opposite end of said barrel formed with an opening transversing said longitudinal bore and a handle having an end detachably carried in said opening for rotating said barrel relatively to 40 said arm.

4. A pair of rotatable members one mounted within the other for relative rotation, one of said members formed with an axially extending bore adapted to receive therethrough the end section 45 of a length of wire engageable about an article and provided with means for receiving a transverse end of a loop formed on the end of said section for maintaining the end in fixed relation with respect to the first defined member upon relative rotation of the latter and looped to enwrap said end about said section proximate said loop, said first defined member formed with a transversely extending bore for receiving the end of the oppositely disposed end section of said length 55 of wire when the last-mentioned end is disposed through said loop for tightening said length of wire about said article upon relative rotation of said members.

5. The structure of claim 4 as set forth and defined therein including, means carried by one of said members for rotating the same with respect to the other.

THEODORE S. WRIGHT. 65
